E. B. HESS

TYPEWRITING MACHINE

Filed Sept. 28, 1921

UNITED STATES PATENT OFFICE.

EDWARD B. HESS, OF MANHATTAN BEACH, NEW YORK, N. Y., ASSIGNOR TO ROYAL TYPEWRITER COMPANY, INC., OF NEW YORK, N. Y., A CORPORATION OF NEW YORK.

TYPEWRITING MACHINE.

Application filed September 28, 1921. Serial No. 503,852.

To all whom it may concern:

Be it known that I, EDWARD B. HESS, a citizen of the United States, residing at Manhattan Beach, in the county of Kings, New York, and State of New York, have invented certain new and useful Improvements in Typewriting Machines, of which the following is a specification.

This invention relates particularly to type actions for typewriting machines and especially to that class of type actions in which the type bars are actuated by the key levers through other levers interposed between the key levers and the type bars and operatively connected therewith.

In my United States Patent No. 1,390,708, of September 13, 1921, I have shown a type action in which the key levers are connected to the type bars by means of levers pivotally mounted in the front portion of the machine and which are connected with the key levers and the type bars by links in a novel way, whereby when a key is depressed to its full extent the associated type bar is moved to what is termed a "toggle-locking or dead-center position" in front of the platen and at such a distance therefrom as to reduce noise during the further movement of the type bar about its pivot to the platen, caused by the momentum of the type bar. In that patent I have claimed broadly connections between the key levers and the type bars which so operate the type bars as to produce the results above specified.

According to my present invention I have embodied some of the broad features shown and claimed in said patent in a type action in which two-armed levers are interposed between the key levers and the type bars and are connected with the key levers and the type bars in a novel way and in such manner that when a key is depressed to its full extent an associated type bar is moved to a position in front of the platen and at such a distance therefrom as to reduce noise during the further movement of the type bar about its pivot to the platen. The key levers and the type bars are arranged horizontally and the two-armed levers, as before stated, are interposed between the key levers and the type bars, being normally arranged substantially horizontally and are adapted to be moved through an arc of approximately 90°. One arm of each lever is connected

with a key lever, while the other arm of said lever is connected with an associated type bar. The link which connects the two-armed lever with the type bar is pivotally connected with the two-armed lever and with the type bar below the pivot of the type bar and approximately in the same vertical plane therewith. The organization is such that when a key is depressed to its full extent the type bar is moved part-way to the printing point, its further movement being caused by its momentum. The pivotal point between the said link and the heel of the type bar moves during the operation from a position below the type bar pivot forwardly and upwardly, there being no movement of said connection substantially in rear of the plane of the type bar pivot. During the operation the opposite ends of the link which are pivoted to the heel of the type bar and to the two-armed lever are brought into a straight line with the pivot of the type bar with which it is connected, thus assuming a toggle-locking or dead-center position. After this there is no further downward movement of the key lever but a slight upward or return movement is given thereto when the parts pass the dead-center position and during the momentum period as the type bar approaches the printing point. Each two-armed lever is link-connected with an associated key lever and during the operation the pivotal connections between the opposite ends of a link, a key lever and a two-armed lever are brought into a straight line with the axis about which the two-armed lever moves, but during the momentum period this condition is changed and the pivot point of the link with the two-armed lever moves backwards to a slight extent and this is during the time that the dead-center condition of the link with the type bar is changed.

The universal bar is preferably located below the key levers and is operated directly thereby. An arm of the universal bar is connected by a link with a lever mounted on the escapement frame which operates on the escapement rocker-plate to operate the rocker feed pawl at the proper time. The arrangement is such that while the universal bar is moved by the key levers when they are first depressed, the escapement mechanism is not operated at this time, but towards the end of

the movement of the key levers the escapement mechanism is operated in the manner hereinafter more fully explained.

My improvements are illustrated in the accompanying drawings, in which,

Figure 1 is a view, largely diagrammatic, of portions of a typewriting machine embodying my improvements, some parts being shown in side elevation and some in section 10 and the position of some of the parts being exaggerated for purposes of illustration;

Figure 2 is a detail view showing particularly how the two-armed levers are mounted on a supporting rod.

Figure 3 is a detail view showing alternative universal bar and key lever relation.

In Fig. 1 of the drawings parts of a typewriter carriage are indicated at A and B indicates a platen. C indicates a type bar 20 segment, D a type bar guide and E parts of a ribbon guide. Escapement mechanism is indicated at F, a key lever at G and a type bar at H. The type bars normally lie horizontally, their rear ends being pivoted 25 to the segment at c and their front ends being supported by a cushioned rest I. The rear ends of the key levers are pivoted at i to a support J and the upward movement of the front portions of the key levers is 30 arrested by a cushioned stop K. Each type bar is returned to normal position by a spring L, attached at one end to the heel of the type bar and at its opposite end to a support L'.

Interposed between the key levers and the type bars is a series of two-armed levers M, there being one such two armed lever for each key lever and its associated type bar. These levers M are all mounted to turn independently on a horizontal rod N, suitably supported in the machine frame. The levers are held suitable distances apart by spacing rings n, as shown in Fig. 2. Each lever M normally lies substantially horizontally, as 40 indicated in Fig. 1, and comprises a short arm m and a longer m'. The shorter arm of each lever is connected by a link O with an adjacent key lever, while the longer arm m' is connected by a link P with the heel of an 45 associated type bar. It will be observed that the pivotal connection x of the link P with the type bar is below the type bar pivot in approximately the same vertical plane therewith and the arrangement is such that 50 when a key is depressed to its full extent the associated type bar will be moved part-way to the printing point, as indicated by dotted lines in Fig. 1. When the type bar reaches this position the pivot point x between the 55 rear end of the link P and the heel of the type bar assumes a toggle-locking or dead-center position with the pivot point c of the type bar and the pivot point y where the link P is connected to the lever M. This 60 condition is indicated by dotted lines in

Fig. 1, where it will be seen that the points c, x and y are in a straight line or dead-center position. No further downward movement is given to the key lever but owing 70

to the momentum of the type bar the latter is carried to the printing point while the key lever has a slight upward movement during this period, which is termed the "momentum period" of the type bar. Each 75 of the connections between the key levers and the type bars operate in a similar way and during this operation each two-armed lever has a movement indicated by dotted lines in Fig. 1. Normally, or when the parts are at rest, the link O is inclined from its lower end upwardly and forwardly. When 80 a key is depressed the shorter arm of the associated lever M is moved downward and rearward, as indicated, through an arc of about 90°. The longer arm of the lever is moved upward and forward to the position shown by dotted lines, where the pivot point z of the link O with the lever M and the pivot point g of the link O with the key lever G are in a straight line with the 85 axis about which the lever turns. When moving to this position the longer arm of the lever moves anti-clockwise and the point y does not move beyond the position shown by dotted lines in Fig. 1. During the momentum period the point y has a slight 90 return movement rearwards. The mechanism is such that the type bars are operated with ease and facility, they are given a quick upward movement to their dead-center 95 position, and by momentum are carried to the printing point in such manner as to materially reduce noise when the type 100 strikes the platen.

The universal bar comprises a rod R horizontally arranged below the key levers and connected by arms r to the support J. The arms r are pivotally mounted in the support and one of these arms is connected with an upwardly extending or vertical arm r', the upper end of which is connected by a link S with a lever T, pivoted at w to the rocker-plate W of the escapement mechanism. This lever T has an arm t, which is normally disposed some distance in front of the rocker-plate as shown. When a key is depressed the universal bar mechanism with which it is connected is also depressed and through the connections shown operates the lever T, but at first the operation is such 110 as to turn the lever T about its pivot w without moving the rocker-plate, but as soon as the arm t comes in contact with the lug w' of the rocker-plate the lever cannot move further about its pivot and therefore the rocker-plate is properly moved to disengage the pawls and the escapement is properly operated. It will be observed that by the 115 mechanism shown and above described the escapement is operated during the latter 120 condition.

part of the movement of the type bars. The escapement mechanism shown, except in the particulars above described, is similar to that used in the Royal standard machine. 5 The links S may be adjusted by the devices s to properly operate the mechanism and it will be observed, by reference to Fig. 1, that the link S is inclined from its front end rearwardly, its connection at s' with the lower end of the lever T being somewhat lower than the connection of the link with the upper end of the arm r'. In this way the carriage with the escapement mechanism may be raised and lowered for case printing without disturbing the relation of the parts.

A spring V connects the arm r' with the frame part V'. The springs L, which return the type bars to normal position, hold 20 them at rest and prevent them from vibrating, are somewhat stronger than the spring V. The construction shown affords a rapid disengagement of the escapement pawls by comparatively small movement of the universal bar. The relation of each key lever with the universal bar mechanism and escapement mechanism is such that the depression of a key operates the escapement mechanism during the latter part of the 25 movement of the key. When a key rises to normal position the escapement operating mechanism assumes a normal position ready for the next operation. By employing springs L of greater tension than the spring 30 V, the type action is restored promptly to normal position, these springs being strong enough to move the two-armed levers from their dead-center position at each operation.

In Figure 3 I have shown a modification 40 in which the lever T, shown in Figure 1, is omitted. In this way, the lost motion between the arm t of the lever T and the ear w' of the rocker is transferred to a space between the universal bar R and the key 45 levers. In this way noise is somewhat reduced. In Figure 3, the link S instead of being connected to a lever is connected directly to the rocker plate.

I claim as my invention:

1. In a typewriting machine, the combination with key levers and type bars, of connections between each key lever and its associated type bar comprising a two-armed lever operatively connected to both the key 50 lever and type bar so that a full depression of the key lever produces a dead center relation of parts in two separate portions of said connections, with the type bar at a distance from the platen from which position it completes its travel by momentum alone, thus reducing noise.

2. In a typewriting machine, the combination with key levers and type bars, of connections between each key lever and its associated type bar comprising an intermediate

lever operatively connected to both the key lever and the type bar so that a full depression of the key lever produces a dead center relation of parts in a plurality of places in said connections, with the type bar 70 at a distance from the platen from which position it completes its travel by momentum alone, thus reducing noise.

3. In a typewriting machine, the combination with key levers and type bars, of connections between each key lever and its associated type bar comprising a lever having unequal arms, a link connecting the longer arm to the type bar, and a link connecting the shorter arm to the key lever, a full depression of the key lever moving each link to a dead center or toggle locking position with the type bar at a distance from the platen, from which position it completes its travel by momentum alone, thus reducing 80 noise.

4. In a typewriting machine, the combination with key levers and type bars, of connections between each key lever and its associated type bar comprising a lever, a link connecting the lever to the type bar, and a link connecting the lever to the key lever, a full depression of the key lever moving each link to a dead center or toggle locking 90 position with the type bar at a distance from the platen, from which position it completes its travel by momentum alone, thus reducing 95 noise.

5. In a typewriting machine, the combination with key levers and type bars, of connections between each key lever and its associated type bar comprising a lever, a link connecting the lever and the type bar, and a link connecting the lever and the key lever, a full depression of the key lever moving 100 the first link to a position where its ends lie in a straight line with the pivot of the type bar, and the second link to a position where its ends lie in a straight line with the pivot 105 of the lever itself, the type bar at this time being at a distance from the platen and completing its travel by momentum alone, thus reducing noise.

6. In a typewriting machine, the combination with key levers and type bars, of connections between each key lever and its associated type bar comprising a plurality of links, each of which is moved by a full depression of a key lever to a toggle locking 110 position with the type bar at a distance from the platen, from which position it completes its travel by momentum alone, thus reducing 115 noise.

7. In a typewriting machine the combination with the key levers of escapement mechanism comprising a rocker-plate, a lever pivotally mounted on the rocker-plate and having an arm adapted to engage the rocker-plate, a universal bar operated by 120 the key levers, and connections between the 125

universal bar and the lever carried by the rocker-plate.

8. In a typewriting machine, the combination with a universal bar, of escapement mechanism comprising a rocker plate, a lever pivotally mounted intermediate its ends on the rocker plate and having one end in position to engage the rocker plate after a predetermined movement, and connections

between the other end of the lever and the universal bar, whereby the movement of the universal bar first moves the lever independently of the rocker plate and then moves the lever and the rocker plate.

In testimony whereof I have hereunto 15 subscribed my name.

EDWARD B. HESS.
